US00D868782S

(12) **United States Design Patent** (10) **Patent No.:** **US D868,782 S**
Adenau (45) **Date of Patent:** **** Dec. 3, 2019**

(54) **PART OF LIGHTING CONTROL**(71) Applicant: **MA Lighting Technology GmbH**,
Waldbuettelbrunn (DE)(72) Inventor: **Michael Adenau**, Würzburg (DE)(73) Assignee: **MA Lighting Technology GmbH**,
Waldbüttelbrunn (DE)(***) Term: **15 Years**(21) Appl. No.: **29/625,971**(22) Filed: **Nov. 14, 2017**(30) **Foreign Application Priority Data**

Nov. 7, 2017 (EM) 004497402-0037
